US0D1112271S

(12) **United States Design Patent** (10) **Patent No.:** **US D1,112,271 S**
Min (45) **Date of Patent:** **** Feb. 10, 2026**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventor: **Yuri Min**, Suwon-si (KR)

(73) Assignee: **SAMSUNG ELECTRONICS CO., LTD.**, Gyeonggi-Do (KR)

(**) Term: **15 Years**

(21) Appl. No.: **29/926,635**

(22) Filed: **Jan. 31, 2024**

(30) **Foreign Application Priority Data**

Aug. 4, 2023 (KR) 30-2023-0030490

(51) **LOC (15) Cl.** **14-04**

(52) **U.S. Cl.**

USPC **D14/486**

(58) **Field of Classification Search**

USPC D14/485-495

CPC G06F 3/048-04897

(57) **CLAIM**

The ornamental design for a display screen or portion thereof with graphical user interface, as shown and described.

DESCRIPTION

The sole FIGURE is a front view of a display screen or portion thereof with graphical user interface, showing my new design.

The outermost perimeter illustrated by a pair of dashed broken lines depicts the display screen or portion thereof and forms no part of the claimed design. The remaining dashed broken lines shown in the figure depict portions of the graphical user interface that form no part of the claimed design.

1 Claim, 1 Drawing Sheet
